CLAIM

I claim the ornamental design for a toy paper airplane launcher, as shown and described.

DESCRIPTION

FIG. 1 is a front perspective view of a toy paper airplane launcher.

FIG. 2 is a rear perspective view of the toy paper airplane launcher of FIG. 1.

FIG. 3 is a side view of the right side of the toy paper airplane launcher of FIG. 1.

FIG. 4 is a side view of the left side of the toy paper airplane launcher of FIG. 1.

FIG. 5 is a top view of the toy paper airplane launcher of FIG. 1.

FIG. 6 is a bottom view of the toy paper airplane launcher of FIG. 1.

FIG. 7 is a front view of the toy paper airplane launcher of FIG. 1; and,

FIG. 8 is a back view of the toy paper airplane launcher of FIG. 1.

In the drawings, the broken lines depict portions of the toy paper airplane launcher that form no part of the claimed design.
